UNITED STATES PATENT OFFICE.

ALBERT UNGFELDT, OF NEW YORK, N. Y.

DESIGN FOR A SAFETY-PIN.

SPECIFICATION forming part of Design No. 33,018, dated July 31, 1900.

Application filed May 25, 1900. Serial No. 18,012. Term of patent 7 years.

To all whom it may concern:

Be it known that I, ALBERT UNGFELDT, a citizen of the United States, and a resident of New York, in the county of New York and State of New York, have invented and produced a new and original Design for Safety-Pins, of which the following is a specification, reference being had to the accompanying drawings, forming part thereof.

10 Figure 1 is a side view of a safety-pin, showing my new design; Fig. 2, a bottom plan view; Fig. 3, a back plan view; and Figs. 4 and 5 opposite end views, respectively.

15 As shown in the drawings, the leading or material feature of my design consists of an oblong body portion A, which represents an animal's shell and which is circular in cross-section and larger at the middle than at either end. One end of said body portion is provided with spirally-formed grooves a and the

other end with a transverse opening a², one side of the shell or body portion constituting a rigid flange or flap a³, which opens at the bottom longitudinally of said body portion, and one end of said shell or body portion being also provided with a hook a⁴ and the other with a pin a⁵.

Having fully described my invention, I claim as new and desire to secure by Letters Patent—

20 The design for a safety-pin herein shown and described.

In testimony that I claim the foregoing as my invention I have signed my name, in presence of the subscribing witnesses, this 24th 35 day of May, 1900.

ALBERT UNGFELDT.
